UNITED STATES PATENT OFFICE.

JOSEPH M. POWELL, OF BROOKLYN, INDIANA.

CUTTER FOR SHALE-EXCAVATORS.

1,129,517.

Specification of Letters Patent. Patented Feb. 23, 1915.

Original application filed August 5, 1912, Serial No. 713,243. Divided and this application filed August 2, 1913. Serial No. 782,581.

To all whom it may concern:

Be it known that I, JOSEPH M. POWELL, a citizen of the United States, residing at Brooklyn, in the county of Morgan and 5 State of Indiana, have invented a new and useful Cutter for Shale-Excavators, of which the following is a specification.

In the manufacture of brick, drain tile, etc., natural deposits of clay, shale, etc., are 10 used as a basis for the plastic. Such natural deposits vary in quality quite materially from top to bottom, so that it is often desirable, and in many cases absolutely essential for economical use, to mix the materials 15 coming from different portions of the deposit. In my co-pending application, Serial No. 713,243, filed Aug. 5, 1912, I have shown an apparatus capable of cutting the entire vertical face of the clay or shale bank 20 under such conditions that a thorough and substantially uniform mixture of the deposit is automatically produced.

The object of the invention set forth in 25 the present application, which is a division of the above mentioned application, is to provide a cutter chain and cutter for operating on such clay or shale deposits, and for especial use in the apparatus in the above mentioned application.

30 The accompanying drawing illustrates my invention.

Figure 1 is a side elevation of the complete apparatus in operative position; Fig. 2 is a fragmentary detail of the cutter 35 chain and cutter; Fig. 3 is a section on the line 3—3 of Fig. 2; Fig. 4 is a fragmentary detail of one side of the cutter chain and its adjacent guide-way; and Fig. 5 is a fragmentary detail of a modified wearing 40 shoe for the cutter chain.

A track 10 is laid on the ground at the bottom of and parallel with the vertical face of a bank 11 from which the clay or shale is to be cut. Mounted on the track 10 are 45 the wheels 12 of a carriage 13, and mounted on the carriage 13 is a main frame or tower 14, which is slidably adjustable upon the carriage 13 transversely of the track 10 by a temper screw 15.

50 At the lower inner corner of the tower 14 is a pair of idler sprockets 17, and vertically above these sprockets, at the upper end of the tower, is a similar pair of idler sprockets 18. Mounted in suitable bearings at the lower end of the tower 14 is a shaft 19 carry-

ing a pair of driving sprockets 21, which are arranged in the vertical planes of the sprockets 17 and 18. Over the three sets of sprockets 17, 18, and 21 is passed a cutter chain 22, which in the present instance comprises a pair of parallel link belts spaced apart. The chain 22 carries any desired number of cutters, each of which consists of a comparatively narrow cutter bit 23 mounted in a holder 24 having a transverse opening 60 25 for the reception of the cutter bit, said cutter bit being held in any one of several possible positions by means of a cross pin 26 taking into one or another of a plurality of notches 27 formed in the bit. The 70 holder 24 comprises a tube or pipe 28 which fits upon a cross pin 29 connecting the pair of link belts forming the chain 22, and at its rear end is provided with a notch or seat 30 which fits upon an adjacent cross pin 29' 75 also connecting such link belts. A scraper 31 precedes and another one follows each cutter 23, these scrapers also extending between the two link belts forming the chain 22. In addition, each holder 24 also acts as 80 a scraper.

The vertical working face of the tower 14 is provided with two vertical guides 32 for the reception and support of the active portions of the two link belts forming the 85 chain 22, and said chain is provided at suitable points, preferably at the links which carry the pins 29 and 29', with wearing members to coöperate with the guides. These wearing members may take different 90 forms, such as anti-friction rollers 33, as shown in Fig. 4, or sliding shoes 34, as shown in Fig. 5.

The driving shaft 19 is driven in any suitable manner by a motor 54. If this motor 95 is an electric motor, it is supplied by a feed wire 91, which passes over a support 92 at the top of the tower and is provided with a suitable trolley 93 for engagement with a wire arranged along the top of the bank, the wire 91 conveniently having sufficient slack to permit the placing of a weighted pulley block 94 in the bight thereof. The motor 54 drives the cutter chain 22 so that the cutters 23 move vertically downward 100 along the face of the bank 11, and is also arranged so that it may drive the wheels 12 to propel the carriage 13 in either direction along the track 10. As the chain and the carriage are thus driven, the cutters 23 105

projecting a sufficient distance into the vertical face of the bank 11, comparatively narrow and thin shavings of mud or shale are cut from such face; and as several cutters 5 are simultaneously operating at different points on the bank, these shavings will fall in a substantially uniform mixture. This uniform mixture of shavings falls upon a slanting platform 75, whence it is carried 10 by a carrier 76, also driven by the motor 54, to a car 77 mounted on a track 78 parallel with the track 10. Any of the shavings which pass below the platform 75 are carried by the scrapers 31 and the holders 24 15 up an inclined trough 74 and delivered to the carrier 76. By making the cutters 23 comparatively narrow, no difficulty is experienced upon their striking the stones which are commonly embedded in the clay 20 or shale of the bank.

I claim as my invention:

1. In combination, a pair of parallel endless link belts, cross bars connecting said belts, a plurality of cutter holders mounted 25 on said cross bars, each of said cutter holders comprising a tubular member which fits around one of the cross bars and extends the full distance between the two link belts

and a part which extends transversely to such tube and is provided at its end with a 30 notch open away from such tube and fitting over another cross bar, and cutters held in such cutter holders and projecting transversely to the tubes thereof.

2. In combination, a pair of parallel endless link belts, cross bars connecting said link belts, a plurality of cutter holders each of which is supported on two of said cross bars and is provided with a bit-receiving opening, said bit-receiving openings being 40 close to the forward one of the two cross bars with which the cutter holder is associated, and a plurality of cutter bits mounted in the openings of the various cutter holders, each of said cutter bits extending 45 across the plane determined by the two associated cross bars.

In witness whereof, I, have hereunto set my hand and seal at Indianapolis, Indiana, this thirtieth day of July, A. D. one thousand nine hundred and thirteen.

JOSEPH M. POWELL.
